UNITED STATES PATENT OFFICE.

HENRY L. ZABRISKIE, OF WESTFIELD, NEW JERSEY, ASSIGNOR TO DIEHL MANUFACTURING COMPANY, OF ELIZABETH, NEW JERSEY, A CORPORATION OF NEW JERSEY.

RHEOSTAT.

Application filed July 20, 1921. Serial No. 486,111.

To all whom it may concern:

Be it known that I, HENRY L. ZABRISKIE, a citizen of the United States, residing at Westfield, in the county of Union and State 5 of New Jersey, have invented certain new and useful Improvements in Rheostats, of which the following is a specification, reference being had therein to the accompanying drawings.

10 This invention relates to electrical resistance units or rheostats, more particularly of the type represented in the U. S. patent to Diehl, No. 1,369,407, of February 22, 1921, and has for an object to simplify and improve 15 the rheostat contact arm and the means for mounting it.

Resistance units of the type referred to usually comprise a support of some heat-resisting insulating material, such as porcelain, upon which is wound a length of resistance wire tapped at intervals to a series 20 of contact points over which plays the free end of a resilient contact arm pivoted at its other end to the support. Such a resistance 25 unit is adapted for mounting in a suitable casing carrying an operating arm which transmits motion to the contact arm. In order 30 that the contact arm may be stiff or heavy enough to afford a substantial connection with the operating arm and yet bear resiliently upon the contact points, it has heretofore been the practice to make such contact arm in two sections, one of which is stiff or 35 non-resilient and the other resilient. The non-resilient section is pivoted to the support 40 to swing only in a plane at right angles to the axis of the pivot, and the resilient section is fixed at one end to the stiff section and in effect forms a resilient extension of 45 the latter. Provision is made for connecting the operating arm with the non-resilient section of the contact arm. This construction necessitates the making and assembling of several small parts to provide the plural-sectioned arm.

According to the present improvement, the arm is made of one piece of comparatively stiff or non-resilient stock; the requisite yielding pressure of such arm upon the contact points being provided for by forming the arm with an aperture somewhat larger than the pivot post and by interposing a spring between such arm and a head on the pivot post; the pivoted end of the arm being 55 preferably formed with a down-turned lip

affording a contact segment adapted to bear yieldingly upon a terminal element at the base of the pivot post.

In the accompanying drawings illustrating the preferred embodiment of the invention, Fig. 1 is a top plan view of the resistance unit. Fig. 2 is a bottom plan view of the same. Fig. 3 is a longitudinal vertical section on the line 3—3, Fig. 1. Fig. 4 is a fragmentary bottom plan view of the contact-arm and Fig. 5 is a fragmentary left-end elevation of the resistance unit.

In the specific embodiment of the invention illustrated, 1 indicates a support of suitable insulating material, such as porcelain, which is provided with openings 2 for screws or bolts whereby it may be mounted in any desired place. A series of the usual contact points 3 are mounted at one end of the support while at the other end is mounted a pivot post. The pivot post is preferably formed with an enlarged head 5, a cylindrical body 6, and a reduced cylindrical shank 7 affording a shoulder 8 at the juncture of the body 6 and shank 7. The shank 80 7 enters a suitable aperture in the support 1 and is threaded to receive the holding screw 9 which passes through the terminal plate 10 and secures the latter firmly in electrical contact relation with the pivot post. Interposed between the shoulder 8 and the support 1 is a contact element in the form of a washer 11 which is also firmly held in electrical contact with the pivot post by the screw 9. 90

The contact arm 12, which is of relatively stiff and substantial construction, is preferably bent up from one piece of sheet metal of substantial thickness. The arm 12 may be formed with upwardly bent cheek-pieces or spaced walls 13 between which an extension of an operating lever may be received to shift the arm 12, as disclosed, for example, in said Diehl patent or in the application of Martin Hemleb, Serial No. 333,346, filed 100 October 25, 1919.

At its forward end the arm 12 is reduced in width and troughed slightly in order that it may readily play over the contact points without catching on the latter. At its opposite end the arm 12 is formed with an aperture 14 slightly larger than the post 6 and preferably having rounded walls so as to freely embrace the post 6 and permit a limited tilting movement of the free end 110

of the arm toward and away from the plane of the contacts 3. Preferably, the rearward extremity of the arm 12 is formed with a down-turned toe 15 forming a contact segment adapted to bear upon the contact element or washer 11; the opposite ends of the arm 12 being yieldingly held in contact with one of the contact points 3 and the contact element 11, respectively, by means of the spring 16 surrounding the body 6 of the pivot post and interposed between the head 5 of such post and the body of the contact arm. A washer 17 may be interposed between the spring 16 and arm 12 although it is not essential.

The support 1 is wound as usual, with a resistor or length of resistance wire 18 tapped at intervals to the contacts 3 and connected at one end to the terminal plate 19.

It will be observed that in the construction described, the arm 12 is at all times held in yielding electrical contact with the contact element 11 and that the free end of the arm bears yieldingly upon the contact points, although the arm itself is made in one piece and is relatively stiff and unyielding. The segmental contact surface 20 extending circularly about the post in a plane at right angles to the axis of such post, affords an efficient contact surface of reduced area permitting free turning of the arm 12 about the pivot post and serving to maintain the arm in a plane parallel to the plane of the contact points and to steady the arm 12 against tilting on its longitudinal axis.

Having thus set forth the nature of the invention, what I claim herein is—

1. A rheostat comprising a support, a plurality of resistor connected contact points and a pivot post fixedly mounted on said support, a contact arm having near one end an aperture freely embracing said post and permitting limited tilting movement of said arm transversely of the plane of the contact points, and a spring mounted on said post and serving to press said arm yieldingly upon said contact points.

2. A rheostat comprising a support, a plurality of resistor connected contact points and a pivot post fixedly mounted on said support, a contact element at the base of the pivot post, a contact arm having near one end an aperture freely embracing said post and permitting limited tilting movement of

said arm transversely of the plane of the contact points, and a spring mounted on said post and serving to press said arm upon said contact points and contact element.

3. A rheostat comprising a support, a plurality of resistor connected contact points and a pivot post fixedly mounted on said support, a contact element at the base of the pivot post, a contact arm freely embracing said pivot post and having a down-turned toe adapted to bear upon said contact element, and a spring mounted on said post and serving to hold the contact arm yieldingly in electrical contact with said contact element and a contact point.

4. A rheostat comprising a support, a plurality of resistor connected contact points on said support, a pivot post on said support, a contact element at the base of said pivot post, a contact arm element apertured to freely embrace said post, one of said elements being formed with a contact segment adapted to bear upon the other element, and a spring for yieldingly holding said arm in engagement with said contact element and any one of the contact points to which it may be turned.

5. A rheostat comprising a support, a pivot post mounted on said support and formed at its upper end with an enlarged head, a contact element on said support at the base of said post, a contact arm apertured to freely embrace said post between said head and contact element, said arm being formed adjacent said aperture with a contact segment adapted to bear upon said contact element, a spring surrounding said post between said head and contact arm, and a plurality of resistor connected contact points mounted on said support within range of said arm.

6. A rheostat comprising a support, a plurality of resistor-connected contact points and a contact element carried by said support, a contact arm freely pivoted intermediate its ends on said support and having a limited tilting movement transversely of the plane of the contact points, and a spring acting on said arm between the ends of said arm to hold it yieldingly in contact with said contact element and contact points.

In testimony whereof, I have signed my name to this specification.

HENRY L. ZABRISKIE.
